INDICATOR FOR DESIGNATION STRIP HOLDER

David J. Wexler, Islip Terrace, N. Y.

Application August 1, 1952, Serial No. 302,077

4 Claims. (Cl. 116—135)

1

The present invention relates to visual indicators, and more particularly to sliding indicators of this character which can be applied directly to an existing designation strip holder.

There are many instances where, in addition to the usual designation strip, it is desirable to apply a manually operable visual indicator or visual signal device to the designation strip holder. Designation strip holders are used in conjunction with telephone switchboards, form holders such as hospital chart holders, and many other devices, and the visual indicator of the present invention is for the purpose of showing a particular or special condition, or that some action is to be taken or has been taken, when the indicator is operated to one of its positions.

Generally, the invention comprises a body member which is preferably H-shaped and adapted to be inserted into the designation strip of the indicator and be securely frictionally held thereby, a cover member longitudinally slidable with respect to the cross-bar of the H-shaped body and frictionally held in any desired position of adjustment, and indicia carried by the cross-bar of the H which may be covered or uncovered at will by sliding the cover member to appropriate positions.

Accordingly, an object of the invention is the provision of a visual signal device of this character which may be readily applied to a designation strip holder.

Another object of the invention is the provision of a device of this character comprising indicia and a manually slidable cover member which is movable at will to cover or uncover the indicia, as desired.

Still another object of the invention, is the provision of a device of this character wherein the body member is securely frictionally held in the designation strip holder, the cover member being relatively lightly frictionally held.

Other and further objects will become apparent upon reading the following specification together with the accompanying drawing forming a part hereof.

Referring to the drawing:

Fig. 1 is a front view of a designation strip holder with an embodiment of the invention applied thereto, the cover member being positioned to expose the indicia.

Fig. 2 is an enlarged fragmentary view, similar to Fig. 1, with the cover member positioned to cover the indicia.

Fig. 3 is a sectional view taken along the line 3—3 of Fig. 2, looking in the direction of the arrows.

2

Fig. 4 is an enlarged front view of the H-shaped body member.

Fig. 5 is a bottom view of the body member shown in Fig. 4.

Fig. 6 is an end view of the body member shown in Fig. 4.

Fig. 7 is a perspective view of the manually slidible cover member.

Referring to Fig. 1, a designation strip holder 11 is shown secured by suitable fastening means, such as rivets 12, to a flat surface 13 of any desired object. The designation strip holder 11 comprises extending rounded flat end portions 14 and two parallel inwardly turned flange portions 15 which extend lengthwise of the back or body portion 16, forming two longitudinal grooves or recesses 17 adapted to receive therein a designation strip (not shown) of paper or other suitable material having any desired information appearing thereon. A suitable transparent strip may cover the designation strip, if desired.

An indicator embodying the present invention is shown inserted in the right hand end of the designation strip holder 11, the indicator being designated generally as 20. The indicator 20 comprises a generally H-shaped body portion 21 having a cross-bar 22 and four legs 23 extending outwardly from the cross-bar 22. The cross-bar 22 carries indica 24 on the left half thereof, which, in the embodiment illustrated, may be an area of distinctive color, such as red, for example.

The H-shaped body portion 21 may be formed of any suitable resilient material, but is preferably made of metallic spring material such as Phosphor bronze, for example. As may best be seen in Figs. 5 and 6, the H-shaped body is curved forwardly about two mutually perpendicular axes, in this instance being both the vertical and horizontal axes, so that the four legs 23 extend forwardly with respect to the center of the cross-bar 22. When the H-shaped body 21 is inserted in the longitudinal grooves 17 of the designation strip holder 11, the legs 23 resiliently engage the front walls of the grooves 17 formed by the inner surfaces of the flange portions 15, the pressure of such engagement being sufficient to hold the H-shaped body securely positioned within the designation strip holder 11.

A cover member 25 (Fig. 7) is shown provided with an outwardly curved central portion 26 and two tapering side portions 27 for sliding engagement with the longitudinal grooves 17 of the designation strip holder 11. The cover member 25 is shown provided with a tab portion 28 which may be grasped to assist in sliding the cover

member 25 along the longitudinal grooves 17. The tapered side portions 27 of cover member 25 engage the longitudinal grooves 17 with sufficient frictional force to retain the cover member 25 in any desired position, but insufficient to prevent easy sliding of the cover member by hand, when desired.

The H-shaped body member 21 and the cover member 25 are inserted in the designation strip holder 11, as shown in Figs. 1 to 3. The legs 23 of the H-shaped body 21 limit the sliding movement of the cover member 25 along the longitudinal grooves 17 of the designation strip holder 11. The force of frictional engagement of the legs 23 of the H-shaped body 21 with the walls 15 of the grooves 17 is considerable, so that it may be displaced only intentionally. The indicia 24 on the cross-bar 22 of the H-shaped body 21 may thus be covered or uncovered at will by sliding movement of the cover member 25.

Having thus described my invention, what is claimed is:

1. A device of the class described adapted to be carried by a designation strip holder having inturned lateral flanges forming two parallel longitudinal grooves, said device comprising: an H-shaped body member of resilient material including a cross-bar portion and legs shaped for secure frictional engagement with said grooves; a cover member slidably disposed in said grooves intermediate said legs on top of the cross-bar portion of the H-shaped member and dimensioned to conceal about one-half of said cross-bar portion; and an indicia carried by the cross-bar portion of said H-shaped member, said indicia being covered or uncovered at will by sliding said cover member.

2. A device of the class described adapted to be carried by a designation strip holder having inturned lateral flanges forming two parallel longitudinal grooves, said device comprising: an H-shaped body member of resilient material including a cross-bar portion and legs shaped for secure frictional engagement with said grooves, said H-shaped member being curved in the same direction about two axes intersecting each other at right angles in the center of the cross-bar portion and extending, respectively, longitudinally and transversely of the latter, a cover member of arcuate shape having tapered side portions, said cover member being slidably disposed in said grooves intermediate said legs on top of the cross-bar portion of the H-shaped member to conceal about one-half of said cross-bar portion and being frictionally held in any desired position therealong; and an indicia carried by the cross-bar portion of said H-shaped member, said indicia being covered or uncovered at will by sliding said cover member.

3. A device of the class described adapted to be carried by a designation strip holder having inturned lateral flanges forming two parallel longitudinal grooves, said device comprising: an H-shaped body member of resilient material in-

cluding a cross-bar portion and legs shaped for secure frictional engagement with said grooves, said H-shaped member being curved in the same direction about two axes intersecting each other at right angles in the center of the cross-bar portion and extending, respectively, longitudinally and transversely of the latter, a cover member of arcuate shape having tapered side portions and an outwardly projecting grasping portion, said cover member being slidably disposed in said grooves intermediate said legs on top of the cross-bar portion of the H-shaped member to conceal about one-half of said cross-bar portion and being frictionally held in any desired position therealong; and an indicia carried by the cross-bar portion of said H-shaped member, said indicia being covered or uncovered at will by sliding said cover member.

4. The combination with a designation strip holder having inturned lateral flanges forming two parallel grooves of an indicator device comprising: an H-shaped body member of resilient material including a cross-bar portion and legs integral with and projecting from said cross-bar portion, said H-shaped member being curved in the same direction about two axes intersecting each other at right angles in the center of the cross-bar portion and extending, respectively, lengthwise and transversely of the latter, said H-shaped member being inserted in the strip holder with its cross-bar portion extending in the longitudinal direction of the strip holder and being in secure frictional engagement with the bottom of the latter and its upwardly and outwardly projecting legs engaging the grooves of the strip holder and being in secure frictional contact with the inturned flanges thereof, an arcuate cover member curved about an axis parallel to the longitudinal axis of the strip holder in a direction opposite to the curvature of the H-shaped body member, said cover member extending transversely over the cross-bar portion of the H-shaped member to conceal about one-half of said cross-bar portion and having its depending lateral edges projecting into the grooves of the strip holder between the legs of the H-shaped member with its marginal portions in slideable frictional engagement with the inturned flanges of the strip holder, and indicia carried by the cross-bar portion of said H-shaped member, said indicia being covered or uncovered at will by sliding said cover member.
